UNITED STATES PATENT OFFICE.

ALBERT E. REPENNING, OF OAK PARK, ILLINOIS, ASSIGNOR TO ORANGE-CRUSH COMPANY, OF CHICAGO, ILLINOIS.

DESIGN FOR A DISPENSING FOUNTAIN.

Application filed October 5, 1928. Serial No. 28,382. Term of patent 14 years.

To all whom it may concern:

Be it known that I, ALBERT E. REPENNING, a citizen of the United States, residing at Oak Park, Illinois, have invented a new, original, and ornamental Design for Dispensing Fountain, of which the following is a specification, reference being had to the accompanying drawing, forming a part thereof.

Figure 1 is a front elevation of a dispensing fountain showing my new design. Figure 2 is a reduced side perspective thereof.

I claim:

The ornamental design for a dispensing fountain as shown.

A. E. REPENNING.
